UNITED STATES PATENT OFFICE.

PELLEW LANGFORD ENNOR, OF SAN FRANCISCO, CALIFORNIA.

STEERING APPARATUS FOR VESSELS.

SPECIFICATION forming part of Letters Patent No. 708,332, dated September 2, 1902.

Application filed August 28, 1901. Serial No. 73,580. (No model.)

To all whom it may concern:

Be it known that I, PELLEW LANGFORD ENNOR, a citizen of the United States, residing at San Francisco, county of San Francisco, 5 and State of California, have invented certain new and useful Improvements in Steering Apparatus for Vessels; and I hereby declare the following to be a full, clear, and exact description of the same, reference being had to the accompanying drawings, forming a part of this specification.

My invention relates to certain useful improvements in steering apparatus for vessels operated by water or other fluid under pressure, as hereinafter particularly explained by the aid of drawings forming a part of this specification.

My improvements consist in the combination and arrangement of a pump to produce 20 water-pressure, a double-acting hydraulic cylinder and piston to operate the rudder, a controlling-valve to distribute water to the operating-piston, means to operate the valve from a lever or steering wheel, means to provide for the escape of air from the hydraulic cylinder and to relieve the latter from shock or other pressure, also to avoid a vacuum therein by reason of the momentum of water escaping therefrom, and in other features 25 especially adapted for steamboats navigating narrow and crooked waterways.

The object of my invention is to provide simple self-acting steering-gearing, applicable on vessels of any kind, complete within 30 itself and not subject to shock or derangement of the parts by accidents or impediments common in such apparatus.

Referring to the drawings, Figure I is a diagrammatic elevation, partially in section, 40 of an improved steering apparatus constructed according to my invention, the parts being illustrated in one plane. Fig. II is an enlarged longitudinal section through the controlling-valve. Fig. III is an enlarged section through an air-escape valve; Fig. IV, a section through a snifting or air-inlet valve, and Fig. V a similar section through a safety-valve.

In navigating narrow waterways, such as 50 sloughs and bayous, the rudder-gearing is subject to sudden reversal by the rudders com-

ing in contact with bars and other obstructions, also by reversing the motion of stern-wheel, so that an elasticity of all the parts are required, especially in respect to water-hammer and reversing shocks, and it is to meet these peculiar conditions that my improvements are directed.

The main cylinder 1 is of the ordinary construction, provided with a piston 2, piston-rod 3, packing-glands 4 at each end, and ports 5, that communicate with the pipes 7 and 8.

The controlling mechanism consists of a cylindrical flanged shell 9, pistons 10 and 12, a piston-rod 13, and passages 14, 15, 16, 17, 65 and 18, that communicate, respectively, with the pipes 19, 7, 20, 8, and 21, as shown in Fig. I, 20 being a supply-pipe from the pump 22, and 19 a return or exhaust pipe to the tank 23.

Hauling ropes or chains 24 and 25 are connected to the piston-rod 3, pass over the pulleys 26 to shackle-blocks 27, placed in the bight of the tiller-ropes 28, one end of these being attached to the stanchions 29, and thus double the movement of the portion 28 of 75 these ropes 24 and 25.

At each end of the main cylinder 1 I place air-escape valves 30, that contain buoyant floats 31, preferably made of cork, that when the chamber 32 fills with water rise and close 80 the escape-passages 33, as shown in Fig. III.

In the head 34 of the main cylinder 1 or near its end I place common safety-valves 35, that will open outward at some predetermined pressure adjusted by a screw and 85 spring, as shown in Fig. V, and at 36 and 37 on the pipes 19 and 21 I place snifting or inward-opening valves 38, (shown enlarged in Fig. IV,) the purpose of which will presently be explained.

The controlling-valve is operated by a rack and pinion, as shown in Figs. I and II, or directly by a lever, as the circumstances render most convenient. The lever 39, if not accessible in a pilot-house, can be connected to 95 steering-wheel, or the shaft 40 can be set vertically, with a lever or wheel on the top.

The valves 35 are an important part of my invention. These provide for reverse shocks on the hydraulic apparatus caused by the 100 rudders, of which there are three, striking on bars on the shore or other obstruction, that

suddenly reverses the strain and produces shock in the main cylinder 1 unless it is relieved in this manner.

I do not confine myself to the particular arrangement of parts shown in the drawings, for, as will be understood, such arrangement must in each case depend on the conditions of erection in vessels of various kinds.

The operation is as follows: The pump 22 when started draws water from the tank 23 through the pipe 41 and forces it into the pipe 20, causing and maintaining static pressure in this pipe. When the piston-rod 3 is to be moved to the right to starboard the helm, the lever 39 is moved to the right, as in Fig. I. This draws outward the piston-rod 13 and the pistons 10 and 12 thereon, permitting water from the pipe 20 to pass through the chamber 16 and the perforations 42 in the shell 43 and out at the port 15, through the pipe 7, into the chamber 45 of the main cylinder 1, forcing the piston 2 to the right, as in Fig. I. At the same time the piston 12 uncovers the perforations 44 in the passage 17, so water contained in the chamber 46 of the main cylinder 1 escapes through the pipes 8, 21, and 19 back to the tank 23, the operation being the same as in the case of any double-acting fluid-engine. The reverse movement is the same, so the tiller can be moved in either direction, and when the controlling-valve is in its central position the piston 2 and the tiller will be firmly locked.

In the case of air entering the main cylinder 1 it escapes through the valves 30 until the water reaches the float 31, which will then rise and close the valve. If by force of the rudder or from any other cause the water in the chambers 45 or 46 becomes subjected to undue pressure, the safety-valves 35 open

and permit the water to escape down to the normal pressure and then close automatically.

When the discharge-water from the main cylinder 1 is rapidly flowing through the pipes 7 or 8 and their connections and the controlling-valve is suddenly closed or reversed, the momentum of the escaping water will cause a vacuum and water-hammer. This I prevent by means of snifting-valves 38, attached at 36 and 37 on the pipes 19 and 21, that permit the entrance of air, which after entering these pipes is carried into the tank 23 and escapes. In this manner it will be seen that without accumulators, air vessels, or other supplementary apparatus I am able by the combination of the valves 30, 35, and 38 to avoid concussion, water-hammer, and like impediments common in hydraulic steering-gearing.

I claim as my invention—

In hydraulic steering apparatus, the combination of a main steering-cylinder provided with air-escape valves 30 and water-escape valves 35, a controlling-cylinder provided with air-inlet valves 38, a force-pump for maintaining pressure in the system, a tank for receiving the circulating liquid, a pipe from the pump to the controlling-cylinder, return-pipes from the controlling-cylinder to the tank, and pipes from the controlling-cylinder to the main steering-cylinder, substantially as specified.

In testimony whereof I have signed my name to this specification in the presence of two subscribing witnesses.

PELLEW LANGFORD ENNOR.
